UNITED STATES PATENT OFFICE.

LEONHARD VORPAHL AND HERRMANN POHL, OF BERLIN, GERMANY.

ALBUM-CLASP.

SPECIFICATION forming part of Letters Patent No. 289,363, dated November 27, 1883.

Application filed March 24, 1883. (No model.)

To all whom it may concern:

Be it known that we, LEONHARD VORPAHL and HERRMANN POHL, of Berlin, in the Kingdom of Prussia, and Empire of Germany, have 5 invented certain new and useful Improvements in Album-Clasps, of which the following is a specification.

The extensible album-clasps heretofore in use are composed of several parts that are connected by being soldered, riveted, or screwed together in any suitable manner, whereby the manufacture of the clasps becomes complicated and expensive.

My invention is designed to simplify the construction of album-clasps and render them less expensive; and it consists of an album-clasp which is made of one continuous blank and integral with the bail, and of an interior spring-cushioned piece that is hinged by lugs 20 to the edge-plate or mounting of the cover, and guided in the casing.

In the accompanying drawings, Figure 1 represents the blank from which the casing of my improved album-clasp is made. Fig. 2 is 25 a blank of the interior slide-piece; Fig. 3, a side view of the slide-piece after it has been bent into proper shape. Fig. 4 is an end view of the slide-piece; Fig. 5, a top view of the casing after it has been bent into proper shape 30 from the blank shown in Fig. 1; Fig. 6, an end view of the same; and Figs. 7 and 8 are front and end views, respectively, of the clasp, shown as applied to the album-cover.

Similar letters of reference indicate corresponding parts.

A represents the blank from which the main part or casing of my improved album-clasp is made. The blank A consists of a face-plate, *a*, with a bail, *m*, made integral 40 therewith. The face-plate *a* is connected by a narrow transverse bottom piece, *b*, having a laterally-projecting nose, *c*, at one side thereof, to the rear plate, *d*. The rear plate, *d*, is provided with projections *e e*, one at each side of the 45 connecting-piece *b*. The rear plate, *d*, is made wider than the face-plate *a*, so as to be bent inwardly, as shown in Fig. 5, whereby contacts of proper width for soldering the front and rear plates, *a* and *d*, together, and also 50 guide-casings for the cushioning-spring of the extensible slide-piece B, are obtained.

The slide-piece B, which forms with the

main piece A the album-clasp, is made of a blank, B, which consists of side pieces or shanks, *f f*, end pieces, *g g*, from which the pin-tle-sleeves are bent, projections *h h* at their upper corners, against which the spiral springs abut after they have been placed in position in the guide-casings formed by the ends *d' d'* of the rear plate, *d*. The blank B is curved at 55 the upper edge of its bridge K, and provided with short recesses *h' h'*, adjoining the projections *h h*, as shown in Fig. 2. The curved edge is turned inwardly at right angles to the bridge K and side pieces, *f f*, so as to form an 60 abutment, K', which is guided by the recesses *h' h'* and the inwardly-bent projections *h h*, along the inner guide-edges, *d' d'*, of the rear plate, *d*, of the casing A. The slide-piece B is hinged to the edge-plate or mounting C, applied to one side of the album-cover, while the bail *m* is applied to a stud or button, *l*, of the edge plate or mounting C', applied to the other side of the album-cover, as shown in Figs. 7 and 8. The slide-piece B may be either 65 cushioned by spiral springs, that are interposed between the inwardly-bent projections *e e* at the lower end of the rear wall, *d*, of the casing A, and the projections *h h* at the upper end of the slide-piece B, as indicated in dotted lines in Fig. 7, or a serpentine spring is 70 used, the ends of which are applied to a nick, *p*, in the upper part of the slide-piece B, and the nose *c* on the connecting bottom piece, *b*, as 75 is also shown in dotted lines in Fig. 7. 80 85

As the casing and bail are made from one continuous blank, A, it forms, in connection with the spring-cushioned slide-piece B, an album-clasp of only two parts, which is applied to the edge-plates of the cover in the 80 usual manner, and which is less expensive, stronger, and more durable than the album-clasps heretofore in use, which consists of a greater number of parts.

We are aware that an album-clasp composed 95 of two parts, of which one part slides within the other, and of cushioning-springs to move said parts and apply a pressure to keep the covers of the album closed, has been used heretofore, and we do not claim the same, broadly. 100

Having thus described our invention, we claim as new and desire to secure by Letters Patent—

1. An album-clasp composed of a casing the

walls and bail of which are made from one continuous blank, and of a spring-cushioned slide-piece having guide-shanks, connecting-abutment, and sleeves at the outer ends of the shank, also made from one continuous piece, substantially as set forth.

2. The combination of a casing A, made with its bail *m* from one continuous blank, and provided with end guides, *d d'*, and stop-shoulders *e e*, with spring-cushioned slide-piece B, having sleeves *g g* at the ends of its shanks *ff*, and an abutment, *K'*, and stop-shoulders *h h*, at its upper end, substantially as set forth.

3. A casing for an album-clasp made from a blank, A, composed of a front plate, *a*, having a bail, *m*, integral therewith, a connecting bottom piece, *b*, and a rear plate, *d*, the latter being bent inwardly at the ends, and provided

with inwardly-bent projections *e e* at the lower edge, substantially as and for the purpose set forth.

4. In an album-clasp, the slide-piece B, composed of shanks *ff*, having sleeves *g g* at the lower ends, and of a connecting piece or bridge, *K*, having an abutment, *K'*, recesses *h' h'*, and projections or shoulders *h h*, substantially as specified.

In testimony that we claim the foregoing as our invention we have signed our names in presence of two subscribing witnesses.

LEONHARD VORPAHL.
HERRMANN POHL.
